ABSTRACT OF THE DISCLOSURE

A cleat construction for a football shoe embodying four cleats for the heel and five cleats for the sole in which each cleat is of cube formation presenting a flat square ground engaging surface and having a metallic threaded insert for threaded engagement with a bolt securely fixed to the shoe. A metal heel plate and a separate flexible metal sole plate is disposed between an inner sole and the shoe heel and sole, both being provided with openings through which the bolts extend, the heads of the bolts seating on each plate with each head having lugs on its under face engaging slots in the associated metal plates to prevent rotation of the bolts. Nuts on the bolts serve to fixedly secure the bolts to the plates. Disposed exteriorly of the shoe at the arch portion thereof is a rubber arch support between the sole and heel cleats.

This invention relates to cleats for football shoes.

The primary object of this invention is to provide an improved cleat construction that will improve the traction properties of a football shoe by presenting a larger area of ground engaging surface than is offered by the customary frusto-conical cleats now in use, which will not sink into soft ground, which is strong and rugged, which is of simple construction and low cost, which will minimize ankle sprains and knee breaks and which can easily be mounted on the football shoe.

Another object of this invention is to form the cleat of cube like shape with a metal cup shaped insert having a stem provided with a threaded bore to receive the shank of a bolt fixedly secured by a nut to the heel and/or sole of the football shoe, the nut lying within the cup of the insert when the cleat is attached to the shoe.

A still further object of this invention is to provide within the shoe beneath the inner sole thereof, a metal heel plate and a flexible metal sole plate to which the bolts are fixedly secured in non-rotative engagement.

Yet another object of this invention is to provide at the arch portion of the football shoe an exterior rubber arch support that will serve to assist the football player in his lateral movements in cutting left and right and as an aid in preventing the cleats from digging too deeply in mud areas.

The invention consists also in any other novel features hereinafter set forth in detail in the following description, illustrated by way of example in the accompanying drawing and more particularly pointed out in the appended claims.

In the drawings:

FIGURE 1 is a side view of a football shoe equipped with the cleats and arch support of the invention.

FIGURE 2 is a bottom plan view of the football shoe showing the number and position of the cleats and the exterior arch support.

FIGURE 3 is a perspective view of the arch support.

FIGURE 4 is a detail elevational view partly in section of the toe end of the shoe and the mounting of the forward cleat thereat.

FIGURE 5 is a bottom plan view taken on line 5—5, FIG. 4.

2

FIGURE 6 is a plan view of the heel and sole metal plates for supporting the cleat attaching bolts.

FIGURE 7 is an elevational view of a mounting bolt.

Referring to the drawings in detail, a football shoe 10 is formed with a sole portion 12, a heel portion 14 and a connecting intermediate arch portion 16 in the manner well known.

For attachment to the sole and heel portions of the football shoe there is provided a plurality of cleats 18, there being four for the heel portion and five for the sole portion. On the heel portion 14, the cleats 18 are arranged in parallel relationship longitudinally of the shoe. On the sole portion 16, the cleats 18 are similarly arranged with the odd cleat 18a disposed at the toe end of the sole portion.

The cleats 18, 18a are each identical in construction and attachment and are therefore interchangeable. Each cleat is formed of a molded block of plastic material such as nylon, square in horizontal cross-section and in the preferred dimensions of $\frac{5}{8}$ " x 1" square, and a metal insert 20. As seen in FIGURE 4, the metal insert 20 is provided with an upper cup 22 having an axial depending stem 24. Provided in stem 24 is an internally threaded axial bore 25, and the entire insert 20 is positioned axially in the vertical center of the cleat.

Within the football shoe is the customary inner sole 26 and suitably positioned between the inner sole 26 and the toe and heel portions 12, 14 respectively are separate metal sole and heel plates 27, 27a, see FIG. 6, only the sole plate 27 being shown so positioned, see FIG. 4. The metal sole and heel plates serve as supports for cleat holding members to be hereinafter described, and at least the metal sole plate is flexible in order to permit flexing of the sole when the shoe is worn.

Formed in the metal supporting sole and heel plates 27, 27a are elongated narrow slots 28, each slot extending lengthwise thereof and each slot provided with a central enlarged opening 30. Received in each opening 30 is a bolt 32 having a threaded shank 34 and a rounded head 36 that is relatively thin. Depending from the flat underside of the head 36 is a pair of lugs 38 disposed in diametrical alignment and equally spaced one on each side of shank 34. The bolt 32 is positioned over each slot 28 with the shank 34 extending downwardly through opening 30 and the lugs 38 seated in the slot, see FIG. 4. A nut 40 threaded on shank 34 rigidly secures the bolt in place, with the lugs 38 acting to lock the bolt against rotative movement. As seen in FIG. 4, the head 36 of the bolt seats directly on the metal supporting sole plate 27 and is covered by the inner sole 26. By virtue of being thin and rounded the head 36 cannot be felt by the foot through the inner sole when the football shoe is worn.

The bolt shank 34 extends through an opening 42, see FIG. 4, and preferably has a substantially close fit therewith.

With all of the bolts 32 secured to the sole portion 12 and heel portion 14, a cleat is attached to each bolt by simply threading the cleat thereon. The length of threaded shank 34 is less than the threaded bore 25 in the stem 22 of the insert 20 so as to permit the upper face of the cleat to tightly grip the abutting surface of the sole and heel portions.

In the exterior arch portion 16 of the football shoe there is provided a flat rubber arch insert 44 of somewhat hour-glass shape and of a thickness less than the height of the cleats, and secured to the shoe arch portion 16 in any suitable manner well known in the art of shoe construction. The purpose of the rubber arch is to assist the player in cutting left and right and as an aid in preventing the cleats from digging too deeply in mud areas.

The constructional form of the cleats and their arrangement on the sole and heel portions of the football shoe

will prevent a player wearing the same from not sustaining knee injuries by not allowing the cleats to dig deeply into the ground. The broad ground engaging surface of the cleats provides excellent traction for cutting left and right, stopping and starting from any position, without digging deeply into the ground as do the now existing pointed cleats on football shoes. Football shoes equipped with the cleats of the invention will be more comfortable because of the flat surface of the cleats. Twisted ankles will be at a minimum because of this broad cleat surface as when stepping on soft ground, the flat broad cleats will not allow the shoe to twist out causing ankle sprain. Also by not digging deeply into the ground the cleats of the invention will not immobilize the shoe causing knee injuries when the player is hit. Yet the cleat provides maximum traction. With this particular type of cleat, when a player is tackled, after planting his foot on the ground for a left or right cut, the shoe will "give" because of the flat surface of the cleat preventing a possible knee injury. The provision of nine cleats on the football shoe provides for greater efficiency, safety and comfort over the conventional shoe equipped with seven cleats.

Having described my invention, what I claim as new and desire to secure by Letters Patent is:

1. A football shoe traction construction projecting from the heel and sole portions of the shoe comprising:
  - (a) a plurality of cleats removably attached to the heel and sole portions of the shoe,
  - (b) each cleat presenting a flat ground engaging surface of substantial area,
  - (c) there being four cleats on the heel portion and five cleats on the sole portion,
  - (d) said cleats being arranged in equal parallel rows and with one cleat positioned at the toe end of the sole portion,
  - (e) an exterior arch support secured to said shoe between the heel and sole cleats having a thickness less than the height of said cleats,
  - (f) each cleat is formed of a molded plastic material,
  - (g) a metal cup shaped insert in said cleat having an upper open portion and an axial depending stem provided with a threaded bore,
  - (h) each cleat being four sided of substantially cube formation and the flat ground engaging surface constituting the bottom of the cleat being square,

25

- (i) threaded means fixedly carried by the shoe and projecting from the heel and sole portions thereof for threadedly engaging with the threaded bore of the metal insert stem of the cleat for securing the cleat to the shoe,
- (j) a metal heel plate,
- (k) a flexible metal sole plate,
- (l) an inner sole in the shoe,
- (m) both said metal heel and sole plates being positioned between said inner sole and the shoe heel and sole portions,
- (n) there being a plurality of elongated slots in said metal heel and sole plates,
- (o) each slot having a central enlarged opening,
- (p) said threaded means constituting a headed bolt having a threaded shank extending through each central opening,
- (q) at least one lug depending from the under side of each bolt head and received in an associated elongated slot, and
- (r) a nut on each threaded shank securing the bolt in fixed non-rotative engagement to the metal heel and sole plates.

2. The football shoe traction construction of claim 1, wherein:

- (a) said nut lies in the metal cup of the cleat insert with the upper face of the cleat in abutting engagement with its associated heel and sole portion, and
- (b) each bolt head being thin and rounded.

3. The football shoe traction construction of claim 2, wherein:

- (a) said exterior arch support is formed of rubber of substantially uniform thickness and of substantially hour-glass configuration.
